UNITED STATES PATENT OFFICE

HOWARD J. HOLTJE, OF WOODCLIFF, NEW JERSEY

FLOOR BRUSH

Application filed January 6, 1927. Serial No. 159,331.

The present invention relates to a brush for waxing, scrubbing, cleaning and polishing floors and has for its prime object to provide a brush of this nature having incorporated therein a liquid wax reservoir for feeding the liquid wax to the floor when desired as the brush is used.

Another very important object of the invention lies in the provision of a brush of this nature with means whereby the liquid wax is forced from the reservoir to the floor by the relative swinging movement of the handle in relation to the brush as said brush is moved to and fro upon the floor.

15 A still further very important object of the invention resides in the provision of a brush having a reservoir with a bellows associated therewith and means whereby the operation of the bellows will cause liquid wax 20 to be delivered from the reservoir to the floor during the operation of the brush.

Another important object of the invention resides in the provision of detachable means for engaging the bellows with the handle and 25 is pivotally mounted on the brush so that the swinging movement of the handle in relation to the brush during the to and fro movement of the brush on the floor will cause the operation of the bellows to deliver the liquid wax 30 from the reservoir to the floor.

A particularly important object of the invention resides in the provision of a structure of this nature which is exceedingly simple, comparatively inexpensive to manufacture, 35 thoroughly reliable and efficient in operation, not likely to easily become out of order, and otherwise well adapted to the purpose for which it is designed.

With the above and numerous other objects in view as will appear as the description proceeds, the invention resides in certain novel features of construction and in the combination and arrangement of parts as will be hereinafter more fully described and 45 claimed.

In the drawing:

Figure 1 is a top plan view of the device embodying the features of my invention,

Fig. 2 is a sectional side elevation there-

50 of,

Fig. 3 is an enlarged detail sectional view showing particularly the reservoir and an inverted U-shaped tube associated therewith.

Referring to the drawing in detail, it will be seen that the numeral 5 denotes a brush head which is of a substantial triangular formation having the sides converging forwardly to a point and the base is of a curved formation to provide a seat or recess as at 6 to receive a conduit 7 having a removable closure plug 8 therein. The brush head 5 has bristles 10 mounted therein in the usual well known manner or any other preferred manner. The brush head is provided with an opening 9 in which is mounted in any suitable manner a reservoir 11 for holding a quantity of liquid wax which is poured therein through the conduit 7 which is connected therewith. A plate 12 is fixed to the brush head 5 and another plate 13 is hinged thereto as at 14. Flexible material 15 connects the plates 12 and 13 so as to form therewith a bellows or pneumatic which is denoted generally by the letter B. Plate 13 is provided with an opening 13^a to permit air to enter into the bellows B, and a suitable valve 13^b is associated with the plate 13 and the opening 13^a whereby air entering the bellows B is prevented from escaping therefrom through the opening 13^a. A bracket 16 is mounted on the brush head 5 adjacent the hinge 14 and has pivotally mounted thereto as at 17 a handle 18. A bracket 19 is fixed to the plate 13 of the bellows B and has a laterally extending pin 20. A latch 21 is pivoted as at 22 to an intermediate portion of the handle 18 and is engageable with the pin 20 to lock the bracket 19 in engagement with the handle 18 so that as the handle 18 is rocked when the brush is in use on the floor the bellows or pneumatic 70 will be expanded and contracted. An opening 24 is provided in the plate 12 adjacent the hinge 14 and receives a pipe 25 which depends downwardly through the opening 9 to the front of the reservoir 11 and the lower end thereof is threaded as at 26. A siphon-like conduit 27 the longer leg of which extends from near the bottom of the interior of the reservoir 11 up through an opening in the front wall thereof and through an opening 75

in the upper portion of the pipe 25 the shorter leg then extending downwardly a distance in said pipe 25. An inverted U-shaped pipe 28 has one leg in the reservoir 11 and the other leg exteriorly thereof, the bight or connecting portion thereof extending through the upper portion of the front wall of the reservoir 11. The bight or connecting portion of this inverted U-shaped pipe 28 is provided with a vent opening 29 so as to prevent a continuing siphon action in the pipe 28. The cap 30 is adapted to be threadedly engaged on the exterior end of the inverted U-shaped pipe 28 and may be disengaged therefrom and engaged on the threaded end 26 of the pipe 25. When it is desired to have a small amount of wax discharged from the device, the cap 30 is engaged on the exterior end of the U-shaped pipe 28 and the plug 8 is removed from the conduit 7. As the reservoir is freely vented when the plug 8 is removed from the conduit 7, atmospheric pressure will be exerted on the contents of the reservoir. When the bellows is contracted the air that has been drawn therein through pipe 25 and the opening 13^a by the expanding of the bellows, is forced down through the pipe 25 therein reducing the pressure in the shorter leg of the V-shaped conduit 27, which is disposed in said pipe 25 so that the atmospheric pressure in the reservoir 11, the conduit 7 being open to the air, will cause the wax to flow up through the leg of the conduit 27 which is disposed in the reservoir and down through the shorter leg of the conduit 27 in the pipe 25 so that a certain amount of liquid wax will be delivered to the floor surface over which the brush is being pushed. This flow of wax will stop immediately upon the expansion of the bellows and thus the flow of wax will be intermittent or of a pulsating nature in relatively small quantities and thus may be efficiently worked into the floor to obtain the best results. If a larger quantity of the wax is desired the cap 30 may be removed from pipe 28, and placed on the threaded end 26 of the pipe 25 and the conduit 7 closed by screwing plug 8 in place and thus when the bellows B is contracted, pressure is created in the reservoir 11 higher than atmospheric pressure as air is forced through the pipe 25 and conduit 27, as will be apparent, so that the wax will be forced out through the inverted U-shaped pipe 28. The vent 29 provided in pipe 28 prevents the liquid from being siphoned from the reservoir so that only the air pressure from the contracting bellows will force the liquid through the pipe 28 in an intermittent flow. The advantage in this invention lies in the ability of the operator to supply the right quantity of wax to the floor. It has, hitherto, been the practice to spill wax on the floor and apply a brush separately. With my improved brush the floor will be supplied with liquid

wax in the necessary quantities thereby preventing waste and softening and cleaning the old waxed surface. Obviously, by disengaging the handle 18 from the bracket 19 the bellows may be rendered inoperative so that the brush may be used without the supply of wax as is desirable, for instance, in using a pad on the brush to take up the excess wax and in polishing.

It is thought that the construction, operation, and utility of this invention will now be apparent to those skilled in this art without a more detailed description thereof. The present embodiment of the invention has been disclosed in detail merely by way of example since in actual practice it attains the features of advantage enumerated as desirable in the statement of the invention and the above description. It will be apparent that changes in the details of construction, and in the combination and arrangement of parts may be resorted to without departing from the spirit or scope of the invention as hereinafter claimed or sacrificing any of its advantages.

Having thus described my invention what I claim as new is:—

1. A brush of the class described comprising a head, a handle pivotally secured thereto, bristles extending from the head, said head provided with an opening, a reservoir mounted in the opening to extend among the bristles, means for filling the reservoir, a bellows on top of the brush head, means connecting said handle and bellows, a pipe extending from the bellows through the opening alongside of the reservoir and communicating with the interior of the bellows, a siphon like conduit extending from the interior of the reservoir and having one leg disposed in said pipe, whereby when air is forced through the pipe by the contraction of the bellows the pressure in the leg of the siphon-like conduit in said pipe is reduced whereby to cause fluid from the reservoir to flow through said siphon-like conduit and be discharged through said pipe.

2. A brush of the class described comprising a head, a handle pivotally connected thereto, bristles extending from the head, said head provided with an opening therethrough, a reservoir mounted in the opening, means for filling the reservoir, a bellows on the brush head, means releasably connecting said handle and bellows, a pipe extending from the bellows and communicating therewith and disposed alongside of the reservoir, a siphon-like conduit extending from the interior of the reservoir and having one leg disposed in the pipe, an inverted U-shaped pipe having one arm extending into the reservoir, the bight portion of said inverted U-shaped pipe being provided with a vent, a cap adapted to be threaded on the exterior end of the inverted U-shaped pipe and also engageable with the end of the first mentioned pipe

whereby to be transferable from one to the other.

3. A brush of the class described comprising a head, a handle pivotally connected thereto, bristles extending from the head, said head provided with an opening therethrough, a reservoir mounted in said opening, means for filling the reservoir, a bellows on the brush head, means releasably connecting said handle and bellows, a pipe extending from the bellows and communicating therewith and disposed alongside of the reservoir, a siphon-like conduit extending from the interior of the reservoir and having one leg disposed in the pipe, vent means associated with the reservoir, said bellows being contractable to force air through the pipe whereby to reduce the pressure in the leg of the siphon-like conduit within said pipe to cause a flow of fluid therethrough from the reservoir.

4. A brush of the class described, comprising in combination, a head, bristles extending therefrom, a handle pivotally connected to said head and adapted to have a rocking movement during travel of the brush over a floor, a reservoir mounted within said head, a conduit for filling said reservoir, a discharge conduit extending from the interior of said reservoir, and means associated with said handle whereby rocking the latter will expel the contents of said reservoir, said means comprising bellows mounted upon said head.

5. A brush of the class described, comprising in combination, a head, bristles extending therefrom, a handle pivotally connected to said head and adapted to have a rocking movement during travel of the brush over a floor, a reservoir mounted within said head, a conduit for filling said reservoir, a discharge conduit extending from the interior of said reservoir, bellows mounted upon said head and associated with said handle, a bracket and latch detachably connecting said handle and bellows, a pipe depending from said bellows and connecting with the interior thereof, a V-shaped discharge conduit extending from the interior of said reservoir and having one leg disposed in said pipe whereby the pressure in the leg of the conduit disposed within the pipe is reduced and the contents caused to flow through said V-shaped conduit and be discharged upon the floor.

6. A brush of the class described, comprising in combination, a head, bristles extending therefrom, a handle pivotally connected to said head and adapted to have a rocking movement during travel of the brush over a floor, a reservoir mounted within said head, a conduit for filling said reservoir, bellows mounted upon said head and associated with said handle, a bracket and latch detachably connecting said handle and bellows, an inverted U-shaped discharge conduit having one arm extending from the interior of said

reservoir, a pipe depending from said bellows and connecting with the interior thereof, a cap adapted to be threaded on the exterior end of said depending pipe, a V-shaped conduit extending from the interior of said reservoir and having one leg disposed in said pipe whereby air may pass from said bellows into said reservoir.

In testimony whereof I affix my signature.
HOWARD J. HOLTJE.
